UNITED STATES PATENT OFFICE.

PAUL BECKER, OF JENA, GERMANY, ASSIGNOR TO THE FIRM OF CARL ZEISS, OF JENA, GERMANY.

DEVICE FOR TEMPORARILY CONVERTING A CONTINUOUS RAY PENCIL INTO AN INTERMITTENT ONE.

1,424,334.

Specification of Letters Patent.

Patented Aug. 1, 1922.

Application filed August 8, 1921. Serial No. 490,722.

To all whom it may concern:

Be it known that I, PAUL BECKER, a citizen of the German Empire, residing at Jena, Germany, have invented a new and useful 5 5 Device for Temporarily Converting a Continuous Ray Pencil into an Intermittent One (for which I have filed applications in Germany, March 19, 1918, No. 348,747; Austria, February 26, 1919), of which the following 10 is a specification.

The present invention relates to a device for temporarily converting a continuously radiating ray pencil into an intermittent one, and containing a circular disc of a substance 15 impervious to light, rotatable about its axis and provided with a number of sections, consecutive in the direction of its circumference.

The subject of the invention is chiefly to 20 be used for giving signals with that kind of phototelegraphy with which there serves as a receiver, a telephone connected to a cell sensitive to light, e. g. a selenium cell, and with which to an observer, looking at the 25 transmitter of the signals, the pencil of rays is always to appear with the same brightness during the transmission of the signals and the intervals between the same. The invention aims at constructing the device in 30 such a manner as to be suited for a corresponding conversion of pencils of rays of a comparatively large cross section as directly produced, e. g. by larger searchlights.

According to the invention this object is 35 attained by disposing parallel to the rotatable disc a number of arms, connected to the pedestal body of the said disc in such a manner, that they may be brought into two different terminal positions, in one of which, 40 when the disc is rotated, they always cover a part as invariable as possible of its segments, whilst in the other position, when the disc is rotated they alternately cover the said segments completely and leave them quite 45 free. Relative to the ray pencil the said device is suitably disposed in such a way that the axis of rotation of the disc coincides with that of the said pencil of rays, so that the diameter of the disc need only be equal to 50 that of the pencil of rays. In the new device the conversion of the pencil of rays into an intermittent one is effected by turning the arms (which should suitably be all coupled to each other) from the first mentioned ter-

55 minal position into that mentioned in the second place. By constructing the arms as thin strips, each of them may, e. g. be rotatably disposed about an axis, running parallel to a radius of the disc. In such case, as the first of the two terminal positions of 60 the arms, in which, when rotating the disc, they cover an always invariable, viz in this case an infinitesimal portion of the segments of the said disc (viewed in the direction of the rays of light which are all supposed to 65 run parallel to each other), that position should be considered, in which the planes of the strips are vertically directed to the disc and as the second terminal position that, in which the planes of the strips run parallel to 70 the disc. If the said device is also to fulfil the other above mentioned condition, viz. that to an observer looking at the transmitter of the signals the pencil of rays appears with the same brightness both during the 75 transmission of the signals and the intervals between the single signals, viz. in the two terminal positions of the arms, the latter must be also provided with a device, by means of which in the first terminal position 80 a certain part of the light is stopped down, because with the periodical interruption of the pencil of light (in the second terminal position of the arms) always a certain, not to be neglected part of the rays penetrating 85 the segments of the disc goes lost.

The necessity of adding to the arms a special stopping device in order to attain a uniform brightness at any time may, however, be suitably avoided by composing each 90 of the arms of two members, each of which being rotatably disposed about one of two pivots, standing both vertically to the plane of the disc, and further by uniting the two members by a joint in such a way that, on 95 the one hand, they may be brought into a position in which they form together a bent arm and, on the other hand, into a position in which they form together a stretched arm. By then disposing, for instance, the journals 100 for the members of the arm in such a way that they lie on a straight line running radially to the axis of rotation of the disc and by further constructing the segments of the disc as radial slits, the same are temporarily 105 quite covered on the disc being rotated, provided the arms are of corresponding size and stretched. By bending, however, the

arms they cross the slits and continually cover them to a certain extent; it can then be easily arranged that, when rotating the disc, the said part will not only be almost invariable but also amount to so much of the entire surface of the slits that the loss of light resulting therefrom will be equal to that, caused by the other position of the arms (with the periodical interruption of the pencil of light).

The annexed drawing shows as a constructional example a device of the last mentioned kind in two sections, viz Fig. 1 a section perpendicular to the axis of the device, Fig. 2 a section parallel to the axis of the device.

This device contains a disc composed of two circular rings a^1 and a^2 and of a number of sector-shaped tins a^3 , uniting the two rings with each other. The ring a^1 forms part of a nave by which the disc is fixed to a shaft b , carrying also a grooved roller b^1 . All tins a^3 are of the same width and are disposed at such a distance apart that the width of the slits remaining between them amounts to one third of that of the tins. The shaft b is supported by a pedestal body c , disposed inside a hollow cylinder d and screwed to the same. The said cylinder is held in position by four tins e (only two of these being shown in the drawing) which connect it as well as the pedestal body c to a casing f . Moreover, between the tins e and the rotatable disc a number of arms are disposed, each of these consisting of a member g^1 and a member g^2 . The members marked g^1 are rotatable each about a pivot h^1 fixed to the casing f and those marked g^2 about a pivot h^2 , fitted to the pedestal body c .

Besides, each member is provided with a slit and in the slits of two members each, forming an arm, there engages a pin i . All pins i are fastened to a ring k , connected by the arms h^1 to a nave h^2 , which is rotatably disposed on the pedestal body c .

Finally, there is connected to the ring k , on the one hand, by means of a band k^3 a spring k^4 fixed to the casing f and, on the other hand, a key k^5 . By means of the said spring k^4 the arms g^1 , g^2 strive to always assume a bent shape and they can continue this endeavour as far as a terminal position which is determined by the touch of the said key k^5 at the upper end of a slit f^1 in the casing f . In this position, when rotating the disc a^1 , a^2 , a^3 the arms cover a part always approximately equal of the slits in the said disc, so that a pencil of light penetrating the slits does not suffer an important interrup-

tion. By turning the ring k by means of the key k^5 opposed to the action of the spring k^4 as far as its lower stop, the arms are brought into a second terminal position. In the latter, shown in the drawing for one of the arms by a dotted line, the members g^1 and g^2 form a stretched arm which, when the disc a^1 , a^2 , a^3 is rotated, temporarily quite covers and temporarily leaves entirely free the slits in this disc.

In order to be used, the said device should be fixed to the casing of a search-light before its front glass in such a manner that the rotatable disc is facing the source of light. By then rotating the disc a^1 , a^2 , a^3 from a motor by means of a cord running over the roller b^1 , it will only be necessary for giving an intermittent, luminous signal to push down the key k^5 opposed to the action of the spring k^4 .

I claim:

1. In a device for temporarily converting a continuous pencil of rays of light into an intermittent one, a circular disc of a substance impervious to light rotatable about its axis and provided with a number of segments, consecutive in the direction of its circumference, a number of arms disposed parallel to the said rotatable disc and rotatably so connected to the pedestal body of the said disc that they may be brought into two different terminal positions, in one of which, on the disc being rotated, they cover a part as invariable as possible of the said segments, whilst in the other one, on the disc being rotated, they alternately cover the segments completely and leave them quite free.

2. In a device for temporarily converting a continuous pencil of rays of light into an intermittent one, a circular disc of a substance impervious to light rotatable about its axis and provided with a number of segments, consecutive in the direction of its circumference, a number of arms disposed parallel to the said rotatable disc, each of the said arms consisting of two members rotatably disposed each about one of two pivots, perpendicular to the plane of the said disc, means for so connecting the said two members to each other that, on the one hand, they form together a bent arm and, on the other hand, they form together a stretched arm.

PAUL BECKER.
